UNITED STATES PATENT OFFICE.

LESLIE DOUGLASS ANDERSON, OF MIDVALE, UTAH, ASSIGNOR TO UNITED STATES SMELTING, REFINING & MINING COMPANY, A CORPORATION OF MAINE.

PROCESS AND APPARATUS FOR CHARGING FURNACES.

1,176,878.

Specification of Letters Patent. Patented Mar. 28, 1916.

Application filed October 5, 1914. Serial No. 865,140.

To all whom it may concern:

Be it known that I, LESLIE DOUGLASS ANDERSON, a citizen of the United States, residing at Midvale, in the county of Salt Lake and State of Utah, have invented certain new and useful Improvements in Processes and Apparatus for Charging Furnaces; and I do hereby declare the following to be a full, clear, and exact description 10 of the invention, such as will enable others skilled in the art to which it appertains to make and use the same.

This invention relates to a process for charging the furnaces of ore treating plants 15 where different grades and classes of ore are to be treated, individually or together, and these various kinds of ore, together with the fluxing, reducing and treating material are separately stored in bins preparatory for 20 treatment.

The special treatment necessary for lead and copper ores has limited the width of the blast furnace by the air pressure which it is practicable to apply at the twyers. The 25 length, however, may be varied considerably and such length depends principally upon the quantity of ore which it is desired to treat. For the sake of tonnage in a furnace for lead ore the length is usually three to 30 four times the width, while a furnace for treating copper may be made much longer than the lead treating furnace. With such a long, narrow furnace, which for convenience will be termed an elongated furnace, it 35 is difficult to obtain a uniform distribution of the charge throughout the entire length of the furnace. The constitution of the components which go to make up the charge are definitely known and the proportion of 40 each component should be accurately measured in order to obtain the best reduction of the metal and to get a slag of a definite constitution. In the furnace treatment of metals the reduction is better and more uniform 45 if the components of the charge are homogeneously mixed and uniformly distributed throughout the length of the furnace. In a copper furnace and especially a lead furnace, it is very important that 50 the components be uniformly distributed throughout the length of the furnace.

For many years the charges were shoveled into the furnace by hand, and in fact many furnaces are hand charged today, which 55 method made it possible for the workman to

judge by the eye where to place the components to get a uniform distribution. The workmen who did the furnace charging had to be highly skilled and therefore, such a system entailed an enormous expense. A 60 later development produced furnace charging cars whose dimensions approximated the inside dimension of the furnace and the components were brought in buggies and mixed in beds and then evenly distributed throughout the length of the car by hand and then these cars were run over the top of the furnace and their contents dropped all at once 65 into the furnace. This system also was dependent on skilled hand labor, and was very 70 expensive.

One object of the present invention is to provide a process for charging furnaces which will do away with skilled hand labor and enable the components of the charge to 75 be handled in such a manner as to uniformly distribute them throughout the length of the furnace. In accordance with this object, one feature of the invention contemplates arranging the components of a charge in 80 layers of substantially uniform length to form a body of material which is approximately the length of the furnace to be charged, and subsequently depositing the body in the furnace as a unit, the components 85 being mixed throughout the length of the body either before or during the deposit in the furnace.

In practising the process in its preferred form, the components of the charge are arranged in layers to uniformly distribute each component throughout the length of a body of material which has a length substantially the same as that of the furnace to be charged, and the layers of material are then 90 mixed, while maintaining the length of the body, to secure a body substantially the length of the furnace to be charged, in which the components of the charge are uniformly 95 and homogeneously distributed. This homogeneously mixed and uniformly distributed body of materials is then taken as a unit and deposited in the furnace, preferably in such a manner that an excess of material will be deposited along a central line parallel to the 100 length of the furnace, thus insuring a uniform treatment of the charge in the furnace.

These and other features of the invention will be readily understood from the following detailed description of the apparatus 110

illustrated in the drawings, and the manner in which it is utilized in practising the method above outlined.

In the drawings, Figure 1 is a front elevation showing more or less diagrammatically a preferred form of apparatus for practising the invention, and Fig. 2 is a similar side elevation, partly in section.

In the apparatus illustrated, the bins A, 10 A¹, A², etc., which are provided for holding the different classes of ore, flux, coke, etc., are elevated above the lorry car C so that the material in the bins will be fed by gravity. Although only three bins are 15 shown, these bins are generally arranged in rows and sufficient in number to contain the necessary supply of charging ingredients for several days run. The general arrangement and elevation of the bins, the elongated furnace B, the lorry car C and charging car D depends upon the topography of the ground upon which the ore treating plant is located, since material from a bin could be elevated by suitable hoisting mechanism to a lorry 20 car as well as be fed by gravity. The cars also could be run up inclines to give them the proper position above one another and above the furnace if the bins and loading tracks were not elevated above the furnaces. 25

30 The storage bins A are supported by a trestle work above a loading track 16 which is also supported by the trestle. The bottoms of the bins have a pair of compartments a, a' at their discharge mouths which 35 supply material from the bin to a pair of endless conveyer feeders 1 and 2 respectively. The feeders 1 and 2 are positioned far enough above the loading track to permit the lorry car C to travel below them 40 when moving along the bins to collect the components of the charge. The components of the charge are discharged from the feeders 1 and 2 into a measuring hopper 12 suspended in the lorry car C and are uniformly 45 distributed throughout the length of the hopper 12. The hopper 12 has a length substantially the same as the length of the elongated furnace B, so that the combined effective feeding width of the feeders is substantially equal to the length of the furnace. 50 The discharge ends of the feeders project out over the hopper 12 at a proper distance to drop the material along the longitudinal center of the hopper 12 so that the components are deposited in layers. 55 Components of the charge collected by this process in the measuring hopper 12 are built up as a body of material which has substantially the same length as the inside length of the furnace, and the relative longitudinal position of the materials, as well 60

as the length of the body, are substantially maintained until the body is deposited in the furnace.

The conveyer feeders consist of a pair of endless belts which travel over a pair of guiding drums 8. The guiding drums 8 at the receiving end of the conveyer are mounted on a driving shaft 5 which is connected by a train of gearing 4 with a connecting gearing 3. The lorry car is preferably provided with an electric motive equipment and has a feeder operating motor 11 mounted on the body of the car at the rear of the measuring hopper 12. The motor 11 has a gear 7 which is positioned to mesh with the feeder connecting gear 3 when the hopper 12 is in register with the feeders 1 and 2. With this construction the lorry car is carefully positioned to insure that the ingredients are uniformly distributed throughout the length of the hopper 12 before the motor 14 can be used to operate the feeders. The feeders 1 and 2 have a flexible coupling 6 connecting their driving shafts 5 so that they are driven in unison to insure that the material will be uniformly discharged into the measuring hopper 12. The bins A have a door 10 located above the feeders which give access to the feeding compartments of the bins to make repairs, and also to place the material in a condition to feed properly.

In collecting a charge for the furnace each ingredient should be accurately weighed, in order to properly balance the amount of flux and reducing material to treat the ore. With the apparatus shown in the drawings, the material is measured by weighing it as it is discharged into the hopper 12 of the lorry car. For this purpose the hopper 12 is suspended from a scale beam 14, and the beam 14 is connected with an indicating beam 15 mounted in the rear end of the lorry car in a position convenient for the car operator.

While the apparatus illustrated above provides a very efficient and convenient means for measuring the material, it may be desirable in some cases to measure the material with any of the well known and approved types of measuring and distributing feeders such as the piston feed, the shaker feeder, or the arc-type discharging gate. When using such types of apparatus, however, they should be constructed to uniformly distribute the ingredients being handled throughout the length of the receiving hopper in which the charge is collected.

In the smelting of some metals, it may be sufficient if the charge of a lorry car, consisting of ingredients arranged in layers uniformly distributed throughout its length, be discharged directly into the furnace, but in the treatment of copper and especially of lead, it is desirable that the ingredients

be thoroughly mixed before being placed in the furnace in order to get the proper reduction. An efficient and successful type of mixer is shown at E. After the charge is deposited in layers in the hopper 12, the car C is run directly over the mixer E and by means of the bottom doors 22 and 23 of the measuring hopper 12, the charge is dumped all at once upon the deflectors 24 of the mixer. The principle of operation of such a mixer is to permit part of the charge to take a vertical drop and retard the remainder with the deflectors so that the retarded part will gradually fill in on the vertically dropping part that preceded it. It will be seen that by the number of deflectors and the angle at which they are set, the proportion which is allowed to drop vertically and the angle at which the retarded portion works into the vertically falling portion, can be governed so as to give a homogeneous mixture.

The mixed charge may be received in the hopper 17 of the charging car D and the mixer is so arranged that the mixed material is uniformly distributed throughout the length of the hopper 17. The length and preferably width of hopper 17 are substantially the same as those of hopper 12 and as stated above, these dimensions approximate the inside dimensions of the furnace to be charged. The body of material formed in the hopper 17 is thoroughly mixed and is in substantially the same shape as that in which it is treated in the furnace. In case it is practicable to run the lorry car over the furnace, the mixer may then be located over the furnace and the charge dumped directly through the mixer into the furnace from the lorry car.

Although a deflector mixer has been described, the invention is not limited to the use of such a mixer since any of the approved types of mixers could be employed which would receive the charge and, homogeneously mix and uniformly distribute it throughout the length of the bed below.

Any of the preferred type of charging cars may be used and these generally have an electric motive equipment. In a type employed the axles are provided with two sets of wheels. The inside set 18, which run on track 20 are larger in diameter than the set 19, on the outside of the car track, in order to carry the weight of the car and hopper when the car is being loaded and while in transit from the furnaces to the mixer. The smaller wheels 19 run on track 21 at the side of the furnace so that the car D is supported at the sides of the hopper 17 while it is discharging into the furnace. The hopper 17 has the usual bottom discharging mechanism so that when it is placed over a furnace the contents may be dumped all at once.

The physical structure of the furnace and the character of chemical action that take place in the charge during treatment cause the central portion of the charge to sink faster than the portion around the sides, 70 so that in placing the charge in the furnace it is desirable to so locate the material that it will sink uniformly and all parts of the charge get the same treatment. By means of the charging mechanism described, a 75 much more uniform and accurate distribution can be obtained than by any other charging system known to the inventor. It will be noted that the feeders are arranged to feed the material at about the center of 80 the lorry car so that the material will be higher at the center than at the sides when placed in the hopper. In the dumping of the charge from the measuring hopper through the mixer E the deflectors 24 are 85 arranged to distribute an excess of material along a vertical central plane parallel to the length of the receiving receptacle. If the material is deposited in the charging car before being placed in the furnace, the 90 transfer of the material from the charging car into the furnace will approximately maintain the excess of material rounded about the vertical central plane of the furnace. By arranging successive charges in 95 the furnace in this way, each charge will sink down and reach the furnace bottom as a unit and all parts of the charge will be uniformly treated.

In carrying out the process, the lorry car 100 is run along the rows of bins A to get the various components of the charge. At each bin the gear 3 is brought to mesh with gearing on the motor 11 and the operator then sets the scale beam and operates the aprons 105 to get a definite amount of each component. These components are arranged in layers uniformly distributed throughout the length of the hopper 12. The lorry car with its weighed charge is then run over the mixer 110 E which may be located over a charging car D or elongated furnace B, and dumps. The blades of the mixer are set at such an angle as to get a thorough mixing, which angle may vary for different characters of 115 the components to be mixed. The charging car when used, upon receiving the intimately mixed charge from the lorry car, is run over the furnace and the charge is dumped all at one time.

By the process outlined above, the ore along with the fluxes and reducing agents for treating it are assembled together, homogeneously mixed and uniformly distributed throughout the length of the furnace in which they are treated. Each ingredient of the charge is measured, and all of the measured ingredients are grouped together to be treated as a body. The charge is deposited in the furnace in such a shape that in sink- 120 125 130

ing under the furnace operation all parts of the charge will receive a uniform treatment. Having each charge a complete independent body permits the treatment of many different kinds of ore in the same furnace during a continuous operation, because each ore, balanced with its treating fluxes and reducing agents, is placed in the furnace as a unit and sinks in the furnace treatment as a unit.

10. Having thus described the invention, what is claimed as new is:—

1. The process of charging elongated furnaces which comprises distributing the components of a charge in separate portions having a substantially uniform length to form a body of material approximately the length of the furnace to be charged, mixing the material to form a body of material of approximately the length of the furnace in which the ingredients are uniformly distributed and homogeneously mixed, and depositing the mixed body of material uniformly throughout the length of the furnace.

2. The process of charging elongated furnaces which comprises uniformly distributing the components of the charge in layers having a substantially uniform length to form a body of material, mixing the body of material while maintaining its length to form a body of material in which the ingredients of the charge are uniformly distributed and homogeneously mixed, and depositing the mixed body of material uniformly throughout the length of the furnace.

3. That step in the process of charging elongated furnaces which comprises distributing the components of the charge in layers of substantially uniform length to form a body of material having approximately the length of the furnace to be charged preparatory to placing the body into the furnace.

4. The process of charging elongated fur-

naces which comprises distributing components of a charge in separate portions having a substantially uniform length to form a body of material approximately the length of the furnace to be charged, mixing the material while maintaining its length to homogeneously mix and uniformly distribute the components of said body, and depositing said body as a unit in the furnace.

5. The process of charging elongated furnaces which comprises distributing the components of a charge in separate portions having a substantially uniform length to form a body of material approximately the length of the furnace to be charged, mixing the body of material to form a body of material in which the components are homogeneously mixed, and distributing the mixed body in the furnace with an excess of material about a vertical central plane parallel to the length of the furnace, so that the charge will receive a uniform furnace treatment.

6. The process of charging elongated furnaces which comprises uniformly distributing the components of a charge in layers having a substantially uniform length to form a body of material approximately the length of the furnace to be charged, mixing the body of material while maintaining its length to form a body of material in which the ingredients are uniformly distributed and homogeneously mixed, and depositing the mixed body of material in the furnace with an excess of material rounded about a vertical central plane parallel to the length of the furnace whereby the body will sink as a unit to obtain a uniform furnace treatment.
